UNITED STATES PATENT OFFICE.

WILLIAM C. SCHULTZ, OF WAUWATOSA, WISCONSIN.

FIRE-EXTINGUISHING APPARATUS.

1,263,291.

Specification of Letters Patent. Patented Apr. 16, 1918.

Application filed March 20, 1915. Serial No. 15,937.

To all whom it may concern:

Be it known that I, WILLIAM C. SCHULTZ, a citizen of the United States, and resident of Wauwatosa, in the county of Milwaukee 5 and State of Wisconsin, have invented certain new and useful Improvements in Fire-Extinguishing Apparatus; and I do hereby declare that the following is a full, clear, and exact description thereof.

10 My invention consists in the apparatus herein particularly set forth with reference to the accompanying drawings and pointed out in the claims of this specification; its object being to prevent spread and rapidly 15 extinguish fire occurring in an oil-storage tank or other structure into which said apparatus has its discharge. Said invention has especial reference to the use of carbon tetrachlorid as a fire extinguishing medium 20 and to the distribution of the same in an atomized condition by means of a gaseous fluid, preferably carbon dioxid gas, under pressure against said carbon tetrachlorid in a container for the two that has a normally 25 sealed discharge conduit having ports therein intermediate of its inlet and outlet to provide for an immediate simultaneous escape of the extinguishing liquid and gaseous fluid through the conduit when the same is un- 30 sealed, said gaseous fluid under pressure constituting the force by which said liquid is expelled therewith in an atomized condition. The carbon dioxid gas is thus saturated with tetrachlorid, and the two extinguishing me- 35 diums then intimately mixed have rapid diffusion and descent in a structure as aforesaid with which my improved apparatus is associated to quickly smother a fire occurring therein.

40 Figure 1 of the drawings represents a vertical sectional view of my improved fire-extinguishing apparatus by which my novel fire-extinguishing process may be made effective, and

45 Fig. 2, a horizontal sectional view of a detail of the apparatus indicated by line 2-2 in Fig. 1.

Referring by numerals to the drawings, 3 indicates a container having a neck reinforcement 4. Screwthreaded in the neck of the container is a shank arm 5 of a hollow fitting constituting part of a-discharge-conduit with which said container is provided, and the inner end of said arm is reduced and 55 recessed. Screwthreaded on the reduction

of said fitting-arm is a nipple 6, and caught between the two is a flange 7 upon an end of a pipe-member 8 of said conduit that extends through the nipple. A bulbous coupling 9 and another pipe-member 10 are shown as 60 constituting parts of the conduit, said pipe-members being connected by the coupling. The conduit extends in the container to near the bottom of the same, and it is provided with ports 11 intermediate of its inlet and outlet. The ports are shown in the coupling-member 9 of the conduit approximately parallel to the bore of said container as a matter of preferred construction for arriving at the best results in practice. 70

A volume 12 of carbon tetrachlorid or other fire extinguishing liquid is placed in the container preferably below the ports of the conduit aforesaid, and the remainder of said container is filled with a gaseous fluid, preferably carbondioxid gas, under pressure. 75

A flexible seal 13 is employed in the recess of the arm 5 of the aforesaid fitting against a stop-piston 14, that has displacement into a shell-arm 15 of said fitting. The 80 piston is held in normal position by a retractive latch 16 in the bore of the nozzle-arm 17 of the fitting at right-angles to the shank-arm 5 of said fitting. The latch is shown tapered at its inner end and engaged 85 with a corresponding notch in said piston, which piston is normally in the intersection of the bores of the fitting above specified.

The latch 16 is part of a shackle 16' coupled to a rod 18 that extends through a 90 sleeve 19, and astraddle of the rod in opposition to a collar 20 on the sleeve is a plug 21 having an outwardly shouldered stem 22 that extends through a hollow arm 23 of the aforesaid fitting into which the plug is retractive. Fast on the stem 7, outside of the fitting-arm 23, is the collar-end 24^a of a lifting rod 24, by which provision is had for manual displacement of the plug 21 to permit retraction of the piston 14 and an automatic displacement of the seal 13, under pressure from within the container, the result being a flow of the contents of said container through the aforesaid conduit. 95

Abutting a collar 25 on the sleeve 19, outward from the nozzle end of the aforesaid fitting, is a tube 26 secured by fusible solder to a tube 27 that is loose on the rod 18, and a nut 28 is run on a screwthread of said rod against the outer end of said tube. 110

A jam-nut 29 is provided on the rod 18 against the nut 28.

Excepting as to the detail of its conduit member, the apparatus above specified is 5 similar to what is shown and described in the application of Herman J. Zottel, filed January 21, 1915, Serial No. 3653, and in my application filed December 31, 1914, Serial No. 879,915.

10 In practice the nozzle of the above described apparatus extends into an oil-storage tank or other structure and said apparatus is manually unsealed, as above described or automatically unsealed, as a result of a melting away of the fusible solder between the tubes 26 and 27 in the event of fire in said structure, whereupon there is an automatic discharge of the contents of the container, the gaseous fluid therein under 15 pressure being the force by which the liquid also in said container is expelled. If the liquid is below the ports 11 of the conduit, some of the gaseous fluid will escape from the nozzle end of the conduit simultaneous 20 with said liquid to atomize the same at the discharge and thus accomplish the result to which my invention is particularly directed. Should it occur that the volume of liquid in the container is over the conduit-ports 25 30 when the container is unsealed, the flow of said liquid will precede that of the gaseous fluid until such time as said ports are uncovered, whereupon the two mediums will flow together through the conduit to have a simultaneous discharge therefrom, and all 35 of said liquid having been discharged, the remaining gaseous fluid is free to discharge and diffuse itself over the mixture of said fluid and atomized liquid. The liquid and 40 gaseous fluid being both fire-extinguishing mediums, the best result is attained by the simultaneous discharge of the two from the conduit of the apparatus in the form of a spray in which they are intimately mixed to thereby intensify the extinguishing effect

of both, and the two chemicals aforesaid have been found best suited to my purpose.

I claim:

1. A fire extinguishing apparatus comprising a container adapted to contain in its lower portion a volume of tetrachlorid and in its upper portion a volume of carbon dioxide gas under pressure, a conduit in the container and extending from near the bottom thereof, an outlet for said conduit outward of the container, and inlet ports in said conduit adapted to be normally disposed above the liquid level, said ports being approximately parallel to the bore of the container, substantially as described. 60

2. A fire extinguishing apparatus comprising a container adapted to contain fire extinguishing mediums, a conduit in the container and extending from near the bottom thereof, said conduit comprising two sections and having a normally sealed outlet and being open at its bottom, a bulbous coupling connecting the sections of said conduit and disposed intermediate the top and bottom of said container, ports in said 65 coupling, said ports being approximately parallel to the bore of the container substantially as described.

3. A fire extinguishing apparatus comprising a container adapted to contain fire extinguishing mediums, a conduit in the container and extending from near the bottom thereof, said conduit having a normally sealed outlet and being open at its bottom, and an enlargement intermediate the ends of 70 75 said conduit, and having inlet ports therein.

In testimony that I claim the foregoing I have hereunto set my hand at Milwaukee in the county of Milwaukee and State of Wisconsin in the presence of two witnesses. 85

WILLIAM C. SCHULTZ.
